WASHING MACHINE

Walter A. Frantz, Shaker Heights, Ohio, assignor
to The Apex Electrical Manufacturing Company, Cleveland, Ohio, a corporation of Ohio

Application April 2, 1938, Serial No. 199,678

7 Claims. (Cl. 192—28)

This invention relates to washing machines and more particularly to an improved drive mechanism for the agitator, wringer and fluid pump of a washing machine.

It is among the objects of my invention to provide a gear mechanism to drive the washing machine agitator and wringer, in which a clutch is arranged to disengage the agitator drive without interrupting the wringer drive, in a novel manner which is more efficient and economical than the clutches heretofore provided to accomplish this result.

It is a further object of my invention to provide a washing machine with a motor, an agitator drive mechanism and a pump, wherein a belt connecting the motor and agitator normally follows a path spaced from the pump and wherein said belt may be moved slightly from its normal path to effect a frictional drive of the pump.

It is a further object of my invention to provide a washing machine in accordance with the preceding object, wherein the belt movement is controlled by a novel spring and toggle arrangement which may be easily manipulated by the user of the washing machine and which will efficiently perform the functions for which it is designed.

It is a further object of my invention to provide a washing machine with an agitator and wringer drive mechanism in which a clutch mechanism having driving and driven parts may be manually operated to effect a smooth and positive engaging or disengaging action between said parts.

It is a further object of my invention to provide a clutch mechanism for a washing machine in accordance with the preceding object in which a part of the clutch controlling mechanism is manually moved and another part is automatically moved in response to the movement of the driving and driven parts of the clutch.

It is a further object of my invention to provide a washing machine with a driving mechanism in accordance with the preceding object, wherein the driving and driven parts of the clutch are coaxially arranged and one of said parts carries a plunger adapted to be received in a complementary recess in the other clutch part.

It is a more specific object of my invention to provide a washing machine with a clutch in accordance with the preceding object in which a plurality of interconnected cam plates smoothly and positively control the movements of said plunger with respect to its recess, to determine

the driving or non-driving relation between the clutch parts.

It is also among the objects of my invention to provide a washing machine drive mechanism wherein continuous rotary motion is converted to oscillating motion to drive an agitator which includes means to prevent end play and noise occasioned by the periodic load variation of the agitator.

10 Further objects and advantages relating to efficiency in operation and economies in manufacture will appear from the following description and the appended drawings, wherein:

Figure 1 is a plan view, with parts broken away, showing a washing machine constructed according to my invention;

Figure 2 is an enlarged partial plan view showing a clutch operating toggle embodied in my invention;

20 Figure 3 is a sectional view taken along the lines indicated at 3—3 in Figure 4, of a gear mechanism constructed in accordance with my invention;

Figure 4 is a plan view of the gear arrangement shown in Figure 3;

Figure 5 is an enlarged sectional elevation taken along the line 5—5 of Figure 4;

Figure 6 is an elevation partly in section taken substantially at right angles to the view of Figure 5;

Figure 7 is an enlarged plan view with parts broken away showing the clutch with the parts thereof in a disengaged position;

Figure 8 is a plan view similar to Figure 7 showing the clutch parts in an engaged position;

Figure 9 is a plan view of a clutch operating cam;

Figure 10 is a sectional view taken along a line 40 10—10 of Figure 8;

Figure 11 is a sectional view taken along the line 11—11 of Figure 8;

Figure 12 is a sectional view taken along the line 12—12 of Figure 8;

45 Figure 13 is a plan view showing the arrangement of the clutch parts and control cams therefor, immediately prior to a disengaging movement of the clutch parts;

Figure 14 is a plan view showing the positions 50 of a clutch control cam during clutch disengagement.

The development of the washing machine art has led to the general acceptance by the industry and trade of that type of washing machine having an oscillating agitator projecting upwardly

within the washing machine tub and a wringer mounted on the tub, wherein both wringer and agitator are driven by a single power unit, such as for instance an electric motor.

Washing machines heretofore provided have also included a clutch between the power unit and agitator so that the agitator drive may be interrupted without affecting the drive to the wringer. Among the disadvantages found in prior art clutch arrangements are those related to the more or less skilled manual manipulation required to control the clutch. The complex nature and cost of certain prior art clutch constructions have also adversely affected their wide general use. According to my invention I propose that numerous disadvantages and defects found in the prior art shall be remedied by the provision of a simple, sturdy clutch which will present marked economy in manufacture and assembly.

Referring to the drawings, the plan view of Figure 1 illustrates a motor 5, a pump 20 and a wringer and agitator drive mechanism 50 mounted through hangers 68 at the under side of a washing machine tub, indicated at 1. As will be understood by those familiar with this art, the tub 1 may be supported in the conventional manner which may include a plurality of supporting legs 3 connected by a ring or skirt 2 with a suitable transverse brace 11 to support the motor and the driving mechanism of the washing machine. The driving mechanism indicated generally at 50 for the agitator shaft 51 and the wringer shaft 52 is preferably enclosed within a gear casing comprising complementary top and bottom halves 53 and 54. The agitator shaft 51 projects upwardly through the center of the bottom of the tub 1 and supports upon its projecting end 55 an agitator of any desirable shape (not shown). The drive for the agitator and wringer is introduced to the gear mechanism 50 through a pulley 58 mounted on pulley shaft 59, which is rotatably mounted within the gear case in a manner more fully described hereinafter. The pulley 58 is preferably formed of complementary sheet metal disks 60 and 61 slotted radially and bent from the plane of the disk adjacent the slots so as to form suitable fan blades 62. The fan thus formed will effect a circulation of the air beneath the tub in a manner to cool and ventilate the motor and gear case. The pulley 58 is provided at its center with an internally threaded nut 63 to secure the pulley to the threaded end 64 of the pulley shaft 59 and the disks 60 and 61, forming the pulley, are bent away from each other at the periphery thereof to form a V-groove to receive the belt 17 which transmits the motor drive to the gear mechanism.

To mount the motor 5 in a manner which will facilitate an adjustment in the tension in the belt 17, the end frame of the motor is secured by screws 6 or other suitable fastenings to a motor support plate 7, pivoted at one end to the brace 11 as at 8. To regulate the tension in the drive belt 17, that end of the motor support plate 7 which is remote from the pivot 8 is slotted as at 9 in a manner which permits bodily swinging of the motor about pivot 8. A thumb screw or other suitable fastener 10 may be arranged through the slot 9 to hold the motor in any selected adjustment.

The wringer shaft 52 and the agitator shaft 51 both receive their driving force from the pulley 58 through its shaft 59 and to transmit the force of drive from the pulley shaft 59 to the agitator and wringer, a gear 70 is rotatably mounted upon

a stub shaft 71 projecting upwardly from the bottom half 54 of the gear case. The gear 70 is a composite gear having teeth 72 at its larger periphery in mesh with teeth 65 on the pulley shaft 59 and teeth 73 in mesh with idler gear 74 of the wringer drive gearing. The gear 74 rotates freely on stub shaft 76 mounted in boss 77 of the lower casing part 54. A gear 75 keyed as at 79 to the wringer shaft 52 establishes a continuous chain of gears from the pulley shaft 59 to the wringer shaft 52 so that the wringer shaft 52 will continue to operate as long as the pulley shaft 59 rotates to drive the gear 70. The lower end of wringer shaft 52 is mounted for free rotation in the casing boss 78 and the upper end is journaled in sleeve 56 carried by the top casing part 53. The continuous rotary motion imparted to the driving gear 70 may be converted to oscillating motion at the agitator shaft 51 by means of the eccentric crank 80 connecting rod 81 and gear teeth 82-83, in accordance with the invention disclosed and claimed in the patent to J. W. Racklyeft No. 2,019,582, November 5, 1935. A pin 91 through rod 81 and bracket 92 journaled on the agitator shaft holds the gears 82-83 in operative relation. The continuous rotary motion of the driving gear 70 may also be converted to oscillating motion at the agitator shaft 51 by a rack and pinion or other similar expedient common to this art.

It will be understood that it is desirable to operate the wringer without actuation of the agitator shaft 51 and to effect selective agitator operation I prefer that the gear 70 be continuously rotated and that a clutch means be interposed between eccentric crank pin 80 and the drive gear 70. The clutch means according to my invention preferably comprises a member 90 which is mounted for free rotation on the bearing hub 84 of the driving gear 70. The member 90 and the driving gear 70 are suitably held in assembled relation on the stub shaft 71 by a washer and cap screw arrangement 85-86. The member 90 in effect comprises the driven part of a clutch wherein the gear 70 functions as the driving part of the clutch. As illustrated in Figure 4, the driven part 90 of the clutch carries the crank pin 80 eccentrically of the center thereof and angularly spaced from the pin is a boss 95 which terminates concentrically with the inner periphery 87 of the driving gear 70. To effect a releasable drive between the clutch parts, the boss 95 is provided with a radially extended guide-way 96 which receives a spring-pressed plunger 97 having a nose portion 100 adapted to be projected into a complementary recess 101 formed at the inner periphery of the driving gear 70.

During the washing operation the composite gear 70 is continuously rotated and through the wringer gears 74 and 75 the wringer shaft 52 is also continuously rotated. As will be understood by those familiar with this art, the wringerhead (not shown) ordinarily carries a clutching device to control the movement of the wringer rolls. Throughout that phase of the washing operation in which the agitator shaft 51 is oscillated to wash the clothes, the nose piece 100 of the driven part of the clutch remains seated in the recess 101 of the driving part of the clutch. This driving or "engaged position" is maintained by the compression spring 103 having one end thereof abutting the end wall 104 of the plunger guide-way 96 and the other end thereof bearing against the end of a bore 105 formed in the plunger 97.

When, however, it is desired to stop the agitator oscillation without interfering with the wringer drive or stopping the power unit drive, the nose 100 of the plunger 96 on the driven part of the clutch is forced from its recess 101 in the driving part of the clutch.

To effect the clutch disengaging action above described, I prefer to employ a plurality of interconnected cam-plates 110, 115 and 120, which are moved at least in part by a manually shiftable control rod 125. The cam plate 110 which will hereinafter be referred to as the bottom cam plate is provided with a non-circular aperture as at 111, to effect a keyed relation with respect to a clutch operating shaft 130 pivoted for rotation in boss 129 formed in the lower half of the gear case 54 (see Figs. 9 and 12). A tail portion 109 on the bottom cam plate 110 limits the plate movement in one direction by bearing against the wall of the casing as shown in Fig. 9. The cam plate 115 which will be referred to as the middle cam plate is arranged on the bottom cam plate 110 and is provided with a circular aperture 116 so that it may rotate freely with respect to the shaft 130 projecting therethrough. The free rotational movement of the middle cam plate 115 with respect to the shaft 130 and the bottom cam plate is limited by an upturned lug 112 on the bottom cam plate 110 which is arranged to move arcuately in the notch 117 of the middle cam plate. A tension spring 113 is hooked in the apertures 108 and 107 of the cam plates 110 and 115, respectively, in a manner normally urging the middle cam plate 115 in a clockwise direction with respect to the shaft 130 so that the lug 112 will assume a position at one end of notch 117 as shown in Figs. 7 and 8.

The cam plate 120, hereinafter referred to as the top cam plate, is pivoted for rocking movement on the cap screw 121 carried by the lower half of the gear case. The top cam plate is arranged with portions overhanging the bottom and middle cam plates and is provided with a notch 122 and hook 123 cooperating with the upturned lug 112 on the bottom cam plate 110.

By referring to Fig. 8 it will be observed that when the clutch operating shaft 130 is turned to the position shown and maintained there by a toggle arrangement more fully hereinafter described, the upturned lug 112 on the bottom cam plate 110 operates to swing the parts to the position shown in this figure. In swinging the top cam plate 120 counter-clockwise about its pivot, the lug 112 bears along the curved notch 122 and through this curved bearing swings the plate 120 until the lug abuts the nose portion or hook 123, and portions of both plates abut the wall of casing part 54. The swinging movement of the plate 120 is accomplished against the tension of a coil spring 124 secured at one end to the cam plate 120 at 128 and at the other end to the operating shaft 130. During the swinging movement of the top cam plate 120 to the position shown in Fig. 8, it will be observed that the middle cam plate 115 is rotated in a clockwise direction in response to spring 113 and as permitted by the notch 117 and the rotation of the lug 112 fitting therein. The positive rotation of the lower cam plate 110 through the spring 113, resiliently pulls the middle cam plate 115 to the position shown in Fig. 8. This position will hereinafter be referred to as the engaged position of the clutch, inasmuch as with the cam parts swung as described, all portions thereof are disposed

outside of the path of boss 95 and the plunger nose 100.

When it is desired to discontinue the agitator action without interrupting the drive to the wringer, the clutch actuating shaft 130 may be rotated in a counter-clockwise direction so as to swing all of the cam plates into the path of the driven clutch parts as best shown in Fig. 13, whereupon the cam surface 127 forming a part of the boss 95 engages the nose or hook 126 on the cam plate 120. Continued rotation of the driving and driven clutch parts in the direction indicated by arrow 39, causes the top cam plate 120 to be rocked upon its pivot 121 in a counter-clockwise direction independently of the bottom and middle cam plates and brings the cam surface 118 of the middle cam plate 115 into engagement with the nose 100 of the plunger. Further rotation of the driving and driven parts of the clutch in the direction of arrow 39, permits a clockwise movement of the hook 126 of the top cam plate into a radially extending recess 98 formed in the boss 95 (see Fig. 10). Said movement of the hook 126 is effected by a spring 124. Simultaneously with the movement of the hook 126 into the recess 98, the middle cam plate 115 turns about its axis 130 in counter-clockwise direction by reason of its engagement with the nose 100 of the plunger 97. The rolling of the middle cam plate, thus described and shown in Fig. 14, forces the plunger 97 radially inward to free the same of the notch 101 in the driving part of the clutch. The hook 126 in recess 98 prevents further rotational movement of the driven part 98. Thereafter the hook 126 bears against a radial wall of the recess 98 as shown in Fig. 7 and the portion 119 of the middle cam plate 115 bears directly against the end of the nose 100 of the plunger to maintain the same out-of-engagement with the driving part of the clutch 70.

With the clutch control and clutch parts in the position last described, the driving gear 70 may continue to rotate in response to the rotation of the power unit and transmit such rotation to the wringer drive shaft 52. The agitator will remain idle during the maintenance of the last described position and this position will therefore be referred to as the disengaged position 50 of the clutch. When it is again desired to operate the agitator of the washing machine, the clutch control shaft 130 may be rotated in a clockwise direction so as to cause the upturned lug 112 of the bottom cam plate 110 to swing the cam plates 115 and 120 to the position shown in Fig. 8, wherein said parts are out of the path of the driven part of the clutch. The resistance to drive through the agitator in the driven part of the clutch will cause said part to remain stationary until the driving part of the clutch has rotated so as to bring the notch 101 into alignment with the nose portion 100. A smooth annular bearing ring is formed on the top radial face of the driving part 78 as at 88 to provide free rotation between the driving and driven parts. As soon as said two parts 100 and 101 are brought into alignment, the spring 103 forces the plunger 97 radially outward to establish a driving relationship between the driving and driven parts of the clutch. Smooth engagement between the driving and driven clutch parts is facilitated by the rounded entrance portion 102 in the notch 101.

From the foregoing description of the three cam plates 110-115-120 and their operating

relation with the driving and driven parts of the clutch, it will be appreciated that the control shaft 130 may be rotated from an engaged to a disengaged position or vice versa, during any phase of operation or at any time without regard to the position of the driving or driven parts of the clutch. The interaction of the cam plates will be appreciated when it is observed that with the clutch shaft 130 rotated clockwise to disengage the clutch, the nose portion of the plunger first engages the middle cam plate 115 and that the middle cam plate is urged to its position of Fig. 13 by a spring 113. Thereafter the surface 110a of 110 holds the nose 100 out of the recess and plate 120 restrains the driven member from rotation. In the event that the plate 115 does not force the nose 100 out of the recess 101, the nose will engage the cam surface 110a of the bottom cam plate. This plate being fixed by its keyed relation to shaft 130 positively forces the nose 100 out of its recess.

To facilitate the manual control of the clutch shaft 130, I preferably fix the upper end 131 thereof to one link 133 of a toggle mechanism indicated in its entirety at 135 (Fig. 2). The link 133 of the toggle mechanism may be conveniently secured to the upper end of the shaft 130 by providing the link 133 with a non-circular aperture to receive a correspondingly shaped end of the shaft 130. The parts may be secured in their assembled relation by a nut 136 and washer 134. The end of the link 133 remote from the shaft 130 is pivotally connected to the other link 137 of the toggle as at 139. The link 137 is bifurcated at its other end as at 138 to embrace a pin 131 projecting from the upper half 53 of the gear casing.

To give the toggle mechanism 135 a desirable snap action, a compression spring 140 is interposed between the pivoted end of the link 137 and the pin 131 projecting from the gear casing in part 53. Intermediate the ends of the link 133 an aperture is provided to receive a down-turned end of the control rod 125. As shown in Fig. 1, the control rod 125 terminates outside of the tub and its supporting structure in a handle 142, conveniently accessible to the operator of the washing machine. By manipulating the control rod from its full-line position in Fig. 1, to its dotted-line position, it will be observed that the toggle 135 will snap from its full-line position (Fig. 2) to its dotted-line position and that this toggle movement is arranged to effect an engaged or disengaged position of the clutch control cams 110-115-120.

Referring again to the manual and automatic phases of the clutch control operation, it will be observed that the operator merely moves the control rod 125 in one direction or the other so as to swing the toggle parts 135 past dead center position and this insures a quick positive movement of the clutch cam plates. The quick positive movement of the clutch cam plates removes from the clutch control mechanism in a practical manner, the human element, and thus obviates any need for the operator of the washing machine to develop any skill or practice such as is required by certain types of clutches to "feel" the clutch parts in and out of engagement. The fact that the human element in the clutch control is in a measure removed, insures that the clutch parts will not be damaged by unskilled, casual or careless motions of the operator.

During the operation of the agitator, the continuously rotating movement of the driving gear

70 is converted to an oscillating movement in the agitator shaft 51 and since the agitator is repeatedly accelerated from an idle position at one end of its oscillation to an idle position at the other end of its operation, there is considerable variation in load thrown into the entire agitator drive mechanism. This variation in load is reflected in the geared engagement between the pulley shaft 59 and the driving gear 70 through the gears 65-72. Helical gears are preferably employed in the geared connection 65-72 which tend to reduce the noise occasioned by the load variations growing out of the agitator operation. To insure a smooth quiet geared drive at 65-72, in spite of any load variations caused by the agitator, I prefer to include in the mounting of the shaft 59 and the gear 65 carried thereby, a means operating to urge the gear and shaft in an axial direction in a manner to eliminate end play of the shaft and gear.

In the preferred embodiment of my invention I effect the above-referred-to function by providing the shaft 59 and gear 65 with an axially extending bore 41 proportioned to receive a compression spring 42 which in turn carries a hardened button 43 at its lower end having an abutting engagement through disk 44 with the lower half 54 of the gear casing. By referring to Fig. 5, it will be understood that the shaft 59 and the gear 65 thereon is supported in the gear carrier through bearings 45 and 46 above and below the gear 65 and that the spring means 42 constantly urges the gear and shaft 65-59 upwardly against a thrust washer bearing 47. From the arrangement I have provided it will also be understood that the variations in load occasioned by the agitator oscillation and the tendency of said variations to produce end play in the pinion drive 65, such end play and attendant noise will be automatically compensated for through the spring mounting.

A further advantage of the spring mounting for the pinion drive 65-72 grows out of the use of helical gears at this point. A sudden application of load, such as turning on the starting motor with the agitator and wringer in gear, will be reflected in relatively high tooth pressures at 65-72. Through the use of helical gears, the tooth pressure at 65-72 will tend to effect longitudinal displacement of the gears with respect to each other. A limited longitudinal movement of the shaft 59 and the gears 65 carried thereby is permitted by compression in the spring 42 and thus the mounting of the pinion gear 65 provides a cushion against suddenly applied heavy loads.

A further advantage associated with the pinion drive assembly I have provided, is related to the ease with which the parts may be assembled. The gear carrier 31 is preferably a casting enclosing the major portion of the shaft 59 and gear 65. An opening 32 is provided to permit the meshing of the gears 65-72, and to mount the gear carrier 31 and gear assembly within the lower half of the gear casing 54, the shaft 59 is inserted through the bottom or large diameter opening of the gear carrier 31. The spring 42 and button 43 may be applied to the shaft 59 and the entire assembly bolted as at 34 through the ears 33 to the bottom half 54 of the gear casing.

A port 35 provided at the top of the casting 31 permits the discharge within the gear casing of any lubricant which may work upwardly along the shaft 59. The groove 36 in shaft 59 entraps upwardly moving lubricant and centrifugally discharges such lubricant through the port 35. A

felt washer 66 around the shaft where it extends through the top half 54 of the gear casing insures against any loss of lubricant at this point.

In accordance with the accepted practice for washing machine gear cases of this type, I propose that the gear case shall be partially filled with a lubricant and that suitable gaskets such as the casing gasket 67 be employed to prevent the loss of any lubricant. From the foregoing description of the construction and operation of the 10 agitator and wringer drive mechanism, it will be appreciated that a mechanism corresponding to my invention will be quiet in operation and will efficiently perform the functions for which it is designed. I preferably include in the driven parts of the washing machine a fluid pump drive which will function to force washing fluid drawn from the bottom of the tub upwardly through a hose (not shown) and discharge the same into a sink or the like above the level of the bottom of 20 the washing machine tub. Since the fluid pump operation is intermittent in that it is not ordinarily required or desired during the washing operation, the most efficient method of operating a fluid pump includes a means whereby the pump impeller rotation may be controlled by the operator.

Although I have described a preferred embodiment of my invention and the several elements entering into the combination which comprises my invention, in considerable detail, it will be appreciated by those skilled in the art that numerous modifications and colorable variations may be made therein without departing from the scope of the invention as defined in the following claims.

I claim:

1. A driving mechanism for a washing machine comprising a driving gear mounted for rotation upon a vertical axis within a casing, a driven member coaxially arranged with respect to said gear, a peripheral portion of said gear formed to encompass a part of said member, said portion provided with a recess and said part provided with a plunger adapted to enter said recess, means to control the position of said plunger with respect to said recess comprising a cam carried by said casing having a portion movable into the circular path described by said recess whereby to engage said plunger and move the same from the recess, a hook operatively connected with said cam provided with a part adapted to be resiliently urged into engagement with said member to restrain the same against movement subsequent to plunger actuation by the cam.

2. A driving mechanism for a washing machine comprising a composite gear operatively associated with a power unit, an agitator drive element coaxially mounted with respect to said composite gear, a clutch interposed between said element and said composite gear provided with a plunger, a recess formed in said composite gear in alignment with the path described by said plunger, means normally urging said plunger into said recess to establish a driving relationship between said member and said composite gear, a manually operated clutch control mounted adjacent the path described by said plunger provided with means to move into said path to force said plunger out of said recess and means controlled by said last-named means to restrain further rotation of said element upon clutch disengagement.

3. A driving mechanism for a washing ma-

chine comprising a rotatable driving gear, a part of said driving gear adapted to be connected to an agitator driving member, clutch means arranged between said member and driving gear comprising a boss formed on said member terminating radially adjacent a peripheral shoulder on said driving gear, a recess formed in said peripheral shoulder, a plunger carried by and movable with respect to said boss to project a portion of the plunger into said recess and establish a driving relation between said driving gear and member, clutch control means comprising a plurality of cams having portions thereof adapted to be moved into the circular path described by said plunger, boss and recess to force said plunger from said recess and restrain said member from rotation with said composite gear.

4. A driving mechanism for a washing machine comprising a drive gear mounted for continuous rotation, a driven member, said gear and member coaxially arranged, a peripheral shoulder having an opening therein formed on said gear, a boss having a spring-pressed plunger formed on said member terminating adjacent said shoulder with the plunger arranged to enter said opening, and means to control the position of said plunger with respect to said opening comprising an element movable into engagement with said plunger to force the same out of the opening and a second element movable into engagement with said boss to prevent rotation of said member while said first-named element operates to hold the plunger out of the opening.

5. A driving mechanism for a washing machine comprising a drive gear mounted for continuous rotation and a coaxially-mounted, driven member connected to a pitman, a peripheral shoulder having a recess formed on said gear, a boss formed on said member terminating adjacent said shoulder, a spring-pressed plunger carried by said boss arranged to enter said recess, means to control the position of said plunger with respect to said recess comprising an element resiliently urged into engagement with said plunger to force the same out of said recess and a second element movable into engagement with said member to prevent rotation of said member subsequent to the movement of the plunger out of the recess and toggle means operatively connected to said elements to maintain their positions of engagement.

6. A driving mechanism for a washing machine having a driving member, a driven member, said members coaxially mounted with respect to each other and a clutch interposed therebetween comprising a spring-pressed plunger carried by the driven member, a recess provided in the driving member in the plane of said plunger and adapted to receive the same, means to control the clutch mounted adjacent the periphery of said members for movement into the path of said clutch parts, said means including one portion movable to engage said plunger and force the same out of said recess, and another portion arranged to engage said driven member to restrain movement thereof subsequent to the plunger movement effected by said first portion.

7. A driving mechanism for a washing machine comprising a driving member, a driven member, a clutch interposed between said members comprising a spring-pressed element carried by the driven member, a recess provided in the driving member in the plane of said element and

adapted to receive a part thereof, means to control the movement of the clutch parts mounted adjacent the periphery of the driving member for movement into the path of said clutch parts, said means comprising a plurality of interconnected plates, one of said plates arranged to engage said element and force the same out of the recess, another of said plates arranged to engage

5 said driven member to prevent movement thereof subsequent to the disengaging element movement and another of said plates provided with means to engage said first two mentioned plates to determine the position thereof with respect to the clutch parts.

WALTER A. FRANTZ.
